CONTROL MECHANISM FOR PNEUMATICALLY OPERATED RAILWAY DUMP CARS

Einar O. Lunde, Wyckoff, N. J., assignor to Magor Car Corporation, New York, N. Y., a corporation of Delaware

Application February 21, 1949, Serial No. 77,655

4 Claims. (Cl. 105—271)

1

This invention relates to control mechanism for pneumatically operated dump cars.

The invention is especially concerned with dump cars having their bodies mounted on the car frames for selective dumping of the bodies to one side or the other of the cars. Such cars are provided with one or more pneumatic cylinders and cooperating pistons on each side thereof, and the present invention is more particularly concerned with mechanism for controlling the flow of air to the cylinders at one or the other side of the cars for dumping thereof in a direction away from the air charged cylinders.

A primary object of the invention is the provision of control mechanism in a pneumatically operated railway dump car provided with an operating air line adapted for control from a locomotive, an air supply reservoir in communication with an air charging line and a dump cylinder at each side of the car; which mechanism includes an adjustable directional valve for selectively directing air to the cylinder at one side or the other of the car, and a valve operative by air pressure in the operating line for causing flow of air from the reservoir through the directional valve and thence into the particular cylinder as determined by adjustment of the directional valve, together with manually operable mechanism supported by the car for adjusting the directional valve.

A further object of the invention is the provision in a structure of the character above referred to, of a manually operable valve disposed on the car, and which valve is operative to provide air pressure in the operating line for effecting operation of the pressure operative valve for flow of air into the selected cylinder in the manner above referred to.

A still further object of the invention is the provision in a pneumatically operated dump car of the character referred to, of an adjustable directional valve for providing flow of air to a cylinder at one side or the other side of a car, and a manually operable valve for causing flow of air through the directional valve, together with manually operable mechanism for adjusting the directional valve and operating the manually operable valve in succession.

A still further object of the invention is the provision of means in the above referred to manually operable mechanism for precluding operation of the manually operable valve until the directional valve has been adjusted.

A further object of the invention is the provision of safety devices for precluding operation

of the control mechanism from one side of the car when same has been operated from the opposite side thereof.

Other objects and advantages of the invention will become apparent in the course of the following detailed description, taken in connection with the accompanying drawing, wherein:

Fig. 1 is a diagrammatic plan view disclosing the general arrangement of the air supply and control means.

Fig. 2 is a broken top plan view of the manual control mechanism.

Fig. 3 is a broken vertical sectional view showing the manual operating valve control rods and associated elements.

Fig. 4 is a side elevational view of the structure of Fig. 2.

Fig. 5 is an enlarged transverse sectional view in the plane of line 5—5 on Fig. 2.

Fig. 6 is an enlarged transverse sectional view in the plane of line 6—6 on Fig. 2.

Fig. 7 is an enlarged transverse sectional view in the plane of line 7—7 on Fig. 2.

Fig. 8 is a vertical sectional view of the manual operating valve.

Fig. 9 is a bottom plan view of the valve shown in Fig. 8.

Fig. 10 is a horizontal sectional view of the valve in the plane of line 10—10 on Fig. 8.

Fig. 11 is a vertical sectional view of a modified embodiment of the valve shown in Figs. 8, 9 and 10.

Fig. 12 is a fragmentary transverse sectional view of a railway dump car to which the present invention is applied.

The mechanism according to the present invention is for use with railway dump cars which are adapted to be dumped toward either side thereof, and such dump cars are preferably provided with a pair of pneumatic cylinders 10 on one side and a like pair of cylinders 11 on the opposite side. A dump car with which the present improved operating mechanism is used is illustrated fragmentally in Fig. 12 and wherein one of the cylinders is shown with its cooperating piston P and piston rod R.

Dump cars of the character under consideration comprise bolsters B from which are supported trunnions T which pivotally support the car body C adjacent each side thereof with provision for either side being raised as is indicated at one side in Fig. 12. The body is provided with releasable side doors D, one of which is shown in open and dumping position in said Fig. 12. The car is shown in this figure as being dumped

toward the left by the pair of cylinders 11 (only one being shown) and this car is capable of being dumped toward the right by the opposite pair of cylinders 10.

The general arrangement of the pneumatic operating mechanism is diagrammatically illustrated in Fig. 1, wherein the operating air line is designated at 12, which line extends beneath and throughout the length of each car of a train thereof, and which lines in a train of cars are coupled at adjacent ends thereof and placed in communication with a control valve in the locomotive which pulls the train of cars.

A charging line 13 is also provided for charging the air reservoir 14 supported beneath each car, this charging line being adapted for connection with the locomotive air supply and the charging line communicates with the reservoir by means of a line 15 which is preferably provided with a check valve 16 and a dirt collector 17.

A branch pipe on air line 18 extends from the line 15 to an automatic operating valve 19 and a manual control valve 20 whereby the reservoir 14, automatic valve 19, and manual control valve 20, are in communication.

Another branch pipe on line 21 connects the manual control valve 20 with the operating line 12, which is also connected with the automatic operating valve 19 through the pipe 22.

In controlling the car dumping operation from the locomotive, the control valve in the locomotive is operated so as to admit air pressure to the operating line 12 on the cars. This air pressure in the line 12 causes the automatic operating valve 19 to function in a manner such as to admit air from the reservoir 14 to a directional valve 23 through the branch pipe 18, a pipe 24 and a branch pipe 25 extending directly from the automatic operating valve 19 to the directional valve 23. The automatic operating valve is disclosed in my co-pending application, Serial No. 103,476, filed July 7, 1949.

The directional valve 23 is disclosed in detail in my co-pending application, Serial No. 82,810, filed March 22, 1949, and said valve is operative to direct the flow of air through pipe 26 to the cylinders 10 or through pipe 27 to the cylinders 11. The directional valve is manually controllable by means of an operating rod 28 having one end thereof operatively connected to the valve as at 29 and its opposite end pivotally connected to one arm of a bell crank lever 30, the other arm of the lever being pivotally connected to an operating rod 31 which extends transversely of the rod 28 and which is disposed adjacent an end of the car.

When controlling the dumping operation from the locomotive, the manual control valve 20 is set in neutral position and there is no flow of air through this valve.

If the dumping operation is to be controlled from a position at any one of the dump cars instead of from the locomotive, the manual control valve 20 on any one of the cars is utilized to effect the control.

By properly setting the operating rod 32 in the "dump" position indicated in Fig. 1, the manual control valve 20 may be set so as to permit the flow of air from the branch pipe 18 through the valve 20, pipe 21 and into the operating line 12.

The flow of air into the operating line 12 will produce the same results as when this line is supplied with air by means of the control valve on the locomotive.

In order to return the cars from the "dump" 75

position to their normal position, the air pressure in the operating line 12 must be exhausted to the atmosphere. If the controlling of the dumping operation has been effected from the locomotive, the exhausting of the operating line 12 is done by means of the control valve on the locomotive.

If, on the other hand, the control of the dumping operation has been effected by use of the manual control valve 20, the operating line 12 is exhausted to the atmosphere by setting the operating rod 32 or the companion operating rod 33 in the "exhaust" position as indicated in Fig. 1. When the operating line has been exhausted, the operating rod 32 or 33 is then placed in "neutral" position.

The action which follows the exhausting of air from the operating line 12 takes place first in the automatic valve 19 through exhaust pipe 34. This valve is caused to function in such manner as to shut off further flow of air from the reservoir 14 and connect the pipe 25 to the atmosphere so as to exhaust the air from the cylinders 10 or 11.

25 The operating rods 31, 32 and 33 and associated parts are shown more in detail in Figs. 2 to 6. The parts are here shown in neutral position in which there is no flow of air possible through either the manual control valve 20 or through the directional valve 23.

The operating rod 31, the bell crank lever 30 and the rod 28 control the operation of the directional valve 23, while the manual control valve 20 is actuated by means of the rotation of the rods 32 or 33.

The operating rods 31, 32 and 33 are disposed beneath a transverse car frame member, shown in dot and dash lines in Figs. 2, 3 and 4, and shown in section in Figs. 5, 6 and 7, and such rods are preferably supported adjacent their opposite ends in brackets 35 and 36 secured to said frame member, and the rod 31 is provided with operating handles 37 at its opposite ends, while rods 32 and 33 are respectively provided with operating handles 38 and 39.

50 The manual control rods 32 and 33 are provided with integral flanges 40 and 41 which are received between pairs of spaced flanges 42 on the directional valve control rod 31, and due to this interlocking of the rods with respect to their lengthwise movement any axial motion of rod 31 is transmitted directly to the operating rods 32 and 33.

The directional valve rod 31 extends through a guide bracket 43 having a hub portion 44 projecting through a recess 45 in a frame member and to which the bracket is rigidly secured. The bracket is provided with a slot 46 opening into an aperture 47 through which the rod 31 loosely extends and the rod is provided with a pair of stops 48 and 49 disposed on opposite sides of the bracket and adapted to pass through the slot 46 upon rotation of the rod to align the stops with the slot.

65 Thus it will be seen that in order to move the rod 31 from the neutral to the dump position, it is necessary to rotate the rod slightly so that one or the other of the stops 48, 49 may pass through the slot 46. The directional valve rod 31 is also provided with a pair of coil springs 50 and 51 disposed between rigid flanges 52 on the rod and the opposite ends of a sleeve 53 slidably supported on the rod and which sleeve is provided with opposed studs 54 engaged in aligned

5

apertures in the adjacent arm of the bell crank lever 30.

These springs act to take up any lost motion in the actuating mechanism for the directional valve 23, and thus insure a proper setting of this valve, and the sleeve 53 permits rotation of the rod 31 independently of the lever 30.

The manual control rod 32 is provided with a pair of diametrically opposed keys 55 and 56, and the companion rod 33 is provided with similar keys 57 and 58.

As is more clearly shown in Fig. 5, the bracket 36 which is equally true of bracket 35 is provided with a plate 59 and an aperture 60 of substantially greater diameter than the rod, which is provided in bracket 36 and plate 59 and through which the rod extends and which rod normally rests on the lower edge of the aperture as in Fig. 5.

The bracket and plate are also provided with a slot 61 opening into aperture 60, and disposed below same and diametrically thereof. The key 58 normally seats in slot 61 while key 57 rests in aperture 60.

While as before stated, the rods 32 and 33 must be rotated to actuate valve 20, they cannot be rotated when in their neutral position due to seating of the keys 58 in the slots 61, and the keys 58 cannot be lifted from the slots while the keys 57 are in the apertures. Thus in order to actuate either rod 32 or 33 it must be moved axially until either key 55 or 57 is moved out of the aperture 60 after which the rod may be lifted to raise key 56 or key 58 out of the slot whereby the rod is free to rotate and actuate the valve 20.

When either of the rods 32 or 33 have been moved axially and rotated, the other rod will be moved axially also but its keys will remain in aperture 60 whereby the other rod cannot be rotated. A sleeve 62 receives the adjacent ends of rods 32 and 33 for free relative rotation of the rods while providing for axial movement of one rod as effected by like movement of the other rod. The sleeve 62 is supported by a plate 63 extending upwardly from a bracket 64 (Fig. 7), which supports the valve 20.

The manual operating valve 20 is provided with an operating lever 65 whose free end normally extends between the spaced adjacent ends of lever operating members 66, each having spaced parallel portions 67 and an arched end portion 68 suitably secured to the respective rod. The portions 67 are engageable with the lever 65 for operating the valve 20.

It is to be noted that rotation of either of the rods 32 or 33 in their normal axial positions as shown in Fig. 2 will not operate the valve 20 for the reason that the operating portions 67 upon rotation of either rod would pass by the valve operating arm 65 without imparting operating movement thereto.

This is a safety feature in the control mechanism wherein the directional valve 23 must be set for dumping of the cars to one side or the other, and accordingly when rod 31 is moved axially to set valve 23, the valve arm operating levers 66 will be moved through the flanges 40, 41 and 42 such that the portions 67 will engage the arm upon rotation of rod 32 or rod 33 as the case may be.

Furthermore, this axial shifting of rods 32 and 33 will move key 55 or key 57 out of aperture 60 whereby the rod 32 or rod 33 may be rotated for operating the valve 20. At this point it is to be noted that the rod 31 is adapted to be pushed

6

toward the center of the car from either side thereof and such operation effects setting of valve 23 for dumping of the car to the side toward which the rod is pushed.

A preferred form of manual control valve 20 is illustrated in Figs. 8, 9 and 10, and in which figures the valve is shown in neutral position as when the cars are in transit. This valve would appear to be more clearly described in connection with its operation and is accordingly described as follows:

In order to dump the cars the valve actuating lever or arm 65 is lifted from its full line neutral position to the dump position indicated in dot and dash lines. Upon initial upward pressure on the lever, the exhaust valve 70 remains on its seat 71 and the pin 72 at the top of the exhaust valve stem 73 acts as a fulcrum for the lever 65. Lifting of the lever 65 will then cause the leak-off valve 74 to move to its seat 75 on the inlet valve 76, and then the continued movement of the valve rod 77 will fully open the inlet valve 76. The valve chamber 78 is in communication with the air line 18. The opening of the inlet valve 76, therefore, will permit the flow of air from the reservoir 14 into the passage 79 and thus to the underside of the check valve 80.

The air pressure will effect opening of the valve 80 and the air will then flow through the ports 81 in the check valve guide 82 and into the valve chamber 83 which is in communication with the air line 21. This will carry the air into the operating line 12 and will thus energize the automatic operating valve 19.

When the air pressure in valve chamber 83 reaches a point where it is approximately equal to the pressure in passage 79, the check valve 80 will automatically seat itself. This action will seal valve chamber 83 from passage 79 and will permit the exhaust valve 70 to control the exhausting of air from the operating line 12. In order to return the cars from the dump position to a normal position, the valve arm or lever 65 must be depressed to the exhaust position as indicated by dot and dash lines in Fig. 8, and this action of the lever will result in the following actions:

First, the exhaust valve 70 will remain on its seat 71 and the pin 72 will act as a fulcrum for the lever 65. The downward movement of the lever will first cause the leak-off valve 74 to leave its seat 75. The leak-off valve will move until the cap 84 at the top of the leak-off valve stem 77 comes into contact with the top of the inlet valve stem 85, and thus cause the inlet valve to close.

This action will permit any air in passage 79 to exhaust to the atmosphere through the leak-off valve 74 and the open ports intermediate the guide lugs 77' at the top of inlet valve stem 85.

When the inlet valve 76 is seated, the pin 86 at the top of cap 84 becomes the fulcrum for the lever 65 and the continued downward movement of the lever will cause the exhaust valve 70 to open.

This action will permit the air in the operating line 12 to escape through the valve chamber 83, past the open exhaust valve 70 and to the atmosphere from the exhaust port 87. After the air pressure in the operating line 12 has thus been exhausted, the lever 65 is placed in its neutral position shown in full lines in Fig. 8.

With the various parts in the neutral position, it will be noted that the check valve 80 will seal the pressure in the operating line valve chamber

83, until such time as the exhaust valve 10 is opened. Any leakage of reservoir pressure past the inlet valve 16 will be permitted to escape to the atmosphere through the open leak-off valve 14 and out through the open ports at the top of 5 the tubular inlet valve stem 35.

A modified embodiment of the inlet valve is shown in Fig. 11 and wherein the inlet valve 18 is provided at the lower end of its shank 35' with a recess 90 whose cylindrical wall is provided with circumferentially spaced vertical chamfers 91 and the leak-off valve comprises a ball 92 which is engaged by a spring 93 from above and by which the ball is normally urged into engagement with a small snap ring 94 seated in the wall 15 of the recess 90.

It will be appreciated from the foregoing disclosure that in accordance with this invention, pneumatic control apparatus for railway dump cars is provided whereby any desired number of cars can be simultaneously dumped, all in the same direction, or in different directions through control of an air valve on a locomotive, and that any particular car can be dumped in either direction through control apparatus associated with 25 such particular car.

While I have disclosed the invention in accordance with but a single specific structural embodiment thereof, such is to be considered as illustrative only, and not restrictive, the scope of the invention being defined in the subjoined claims.

What I claim and desire to secure by United States Letters Patent is:

1. Mechanism for successively operating a directional valve and a manual control valve in the pneumatic operating system of a railway dump car having a frame, comprising a pair of spaced brackets rigid with the frame, a directional valve operating rod mounted in said brackets for both rotatable and axial movement, a pair of axially aligned manual valve operating rods mounted in said brackets for both rotatable and axial movement and being disposed in laterally spaced parallel relation to said first rod, operating connections between said first rod and said directional valve including a bell crank operable upon axial movement of said first rod, means cooperating with said frame and said first rod providing for axial movement thereof in a single rotated position thereof, means on each of said pair of rods engageable with an arm on said manual control valve upon rotation of either rod when in a predetermined axial position, and cooperating means on said first rod and each of said pair of rods for alternately moving said pair of rods to said predetermined axial positions upon corresponding 55

axial movement of said first rod in respective opposite directions, and means cooperating with said brackets and said pair of rods for preventing rotation thereof until moved axially from normal inoperative position upon corresponding axial movement of said first rod.

2. The structure according to claim 1 wherein said first means comprises a bracket rigidly secured to said frame, an aperture in said bracket in which said directional valve operating rod is loosely disposed, a slot in said bracket radially of said aperture and communicating therewith, and a pair of stops on said last rod normally disposed one at each side of said bracket, said stops each being adapted for alignment with said slot upon rotation of said last rod through a predetermined angle thereby providing for axial movement of the rod with one or the other of said stops passing through the said slot.

3. The structure according to claim 1 wherein said third means comprises a flange rigid with each of said pair of rods in right angular relation to the axis thereof, and two pairs of spaced flanges rigid with said directional valve operating rod, each said pair of spaced flanges receiving therebetween one of said first flanges whereby said directional valve operating rod and said pair of rods are constrained to axial movement in unison while being independently rotatable.

4. The structure according to claim 1 wherein said last means comprises a plate rigidly secured to each of said brackets, an aperture in said bracket and plate of substantially greater diameter than a respective one of said pair of rods, a slot in said bracket and plate radially of said aperture and communicating therewith, and a pair of axially elongated keys secured to each of said pair of rods in diametrically opposed relation, the keys of each pair being of different lengths and having corresponding ends thereof aligned, and the shorter keys being normally disposed within said apertures and the longer keys normally disposed within said slots for the purpose described.

EINAR O. LUNDE.
